UNITED STATES PATENT OFFICE.

JOHN ENOCH YOUNGQUIST, OF STERLING, COLORADO.

CROSSING SIGNAL.

Application filed March 29, 1924. Serial No. 702,854.

To all whom it may concern:

Be it known that I, JOHN ENOCH YOUNGQUIST, a citizen of the United States, residing at Sterling, in the county of Logan and State of Colorado, have invented certain new and useful Improvements in Crossing Signals, of which the following is a specification, reference being had to the accompanying drawings.

10 This invention relates to improvements in railway crossing signals and more particularly to a signal adapted for use at highway crossings of railways and particularly grade crossings. An important object 15 of the invention is to provide a device of this character adapted to be positioned centrally of the right of way and operated by the approach of the train, trolley car or the like, to be moved to operative or warning 20 position where it, to a certain degree, obstructs the right of way.

A further object of the invention is to provide a device of this character so constructed that if struck by a vehicle it may 25 yield without injury to either the vehicle or signal.

A still further object of the invention is to provide a movable signal or semaphore of this type having electrical means for 30 moving it to elevated position, including a part releasing the current of the actuating means and maintaining the signal locked in elevated position until the circuit formed by the train passing over a given section of track is broken.

A still further object of the invention is to provide a device of this character which may be very readily constructed and installed, is simple and durable in its operation 40 and which requires minimum of attention.

These and other objects I attain by the construction shown in the accompanying drawings wherein for the purpose of illustration is shown a preferred embodiment 45 of my invention and wherein:—

Figure 1 is a plan view showing a signal constructed in accordance with my invention applied to a railway crossing;

50 Figure 2 is an enlarged sectional view through the signal;

Figure 3 is an enlarged plan view thereof;

Figure 4 is an enlarged detail view show-

ing the operating portion of the signal when in a locked position;

55

Figure 5 is a detail cross sectional view showing the manner of supporting the cover plates;

60

Figure 6 is a detail view showing the construction of the contact 28; and

65

Figure 7 is a detail sectional view showing the mounting of the semaphore arm upon the operating lever.

70

Referring now more particularly to the drawings, the numeral 10 indicates a rectangular casing, the walls of which are preferably formed of concrete, the casing being buried so that its upper surface is flush with the upper surface of the highway, the longitudinal axis of the casing being 75 disposed transversely of the right of way. The casing is provided upon one longitudinal wall thereof with outwardly extending shelf portions 11 co-operating with ledges 12 formed by rabbetting the upper inner 80 edges of the casing to receive a pair of cover plates 13 which meet at the center of the casing and are provided with adjoining coacting slots 14 disposed adjacent the longitudinal side of the casing from that 85 upon which the shelf portions 11 are disposed.

75

Mounted in the upper portion of the longitudinal wall adjacent which the slot 14 is disposed, is a pivot 15 to which is secured a triangular piece of metal forming a bell crank lever generally indicated at 16. One edge of this piece of metal is normally disposed horizontally, as shown in Figure 2 at 17 and the other edge thereof 90 is arranged vertically and has pivoted there-to a semaphore 18 normally disposed in the same general plane as the lever 16 and maintained in such position by the hinge connection of the sections indicated at 19, these 95 hinges embodying springs normally maintaining this alignment but permitting yielding of the plate so that it may move to a position at right angles to the part of the lever at either side thereof. The purpose 100 of this construction will hereinafter become more apparent. Secured to the wall of the casing having a pivot 15 is a spring 20 so positioned that when the semaphore 18 is disposed within the casing or in inoperative 105 position, it abuts thereagainst and its move-

ment is limited. When the lever 16 is operated to elevate the semaphore to the operative position through the slot 14, this lever comes into engagement with the spring 20 and its movement to operative position is thus limited.

Disposed within the bottom of the casing is a solenoid 21, the armature bar 22 of which extends longitudinally of the casing 10 and has secured to its free end a flexible member 23 which is trained over pulley 24 arranged immediately beneath the vertical edge of the lever 16 when in operative position and then secured to the free end of 15 the lever as at 25. When the solenoid 21 is energized, this armature bar is drawn into the winding moving the end 25 of the lever downwardly until it assumes the operative position. By this movement the semaphore 20 18 is shifted upwardly through the slot 14 and appears above the surface of the right of way to provide a warning.

The outer end of the armature bar has secured thereto a lug 26 forming a contact point. Immediately adjacent the outer end of the solenoid an electromagnet 27 is disposed, the armature bar of which has its downward movement limited by a post 28 forming a contact, the armature bar having upon its undersurface a coacting contact 29. The end of the armature bar is provided with an upwardly facing lug 30 and the length of this armature bar is such that when the plunger 22 is fully drawn into the solenoid winding, the lug 26 of the plunger is arranged toward the solenoid winding 21 from the lug 30 of the armature bar. Since the lug 26 faces downwardly, it will be obvious that if this armature bar is now drawn upwardly, the result will be latching of the plunger 22 in its position within the solenoid winding until the armature bar is again released.

In Figure 4 I have shown the wire connections of the signal as above described. The coil windings of the solenoid and electromagnet are connected with one another at one end by a wire 31. From this wire a connection 32 is made to one rail of the railway, it being understood that in a segregated section of the rail the sections at each side of the track are electrically connected to one another. From the second rail a wire 32^a is led to one terminal of a source of current 33 preferably a battery located within the casing 10. In the opposite terminal of this battery a wire 34 is connected with the armature 30^a. From the post 28 a wire 35 is connected to the second terminal of the solenoid winding. From the second terminal of the electromagnet a wire 36 is connected to the contact lug 26 of the plunger 22. This contact is preferably made adjustable longitudinally of the plunger 22, as indicated at 37. With the connections

made as above the operation of the device is as follows. The train entering the electrified zone in the railway completes the circuit as follows: from the battery, through wire 32^a to one rail, across the rails through the 70 train, (not disclosed), through wire 32 to wire 31 completing one side of the circuit to both the solenoid and electromagnet, from the opposite side of the solenoid through wire 35 to contact post 28, contact 29 of the 75 armature 30^a and from this armature through wire 34 to the battery 33. At this time the circuit of the electromagnet is broken between the contacts 26 and the battery 33 so there is no current flowing 80 through the electromagnet. The energizing of the solenoid results in the plunger 22 being drawn into the same with the result that the side 17 of the lever 16 is moved to a vertical position and the semaphore 18 is 85 shifted upwardly through the slot, movement in this direction being limited by the engagement of the lever 16 with the spring 20. As the plunger 22 moves inwardly, the contact lug 26 thereof immediately before the 90 plunger reaches the limit of its movement has a brush engagement with the contact 30 with result that a circuit is completed from the second contact of the electromagnet 27 through wire 36, contact 26, contact 30, armature bar 30^a, wire 34 to the battery thus 95 completing the circuit of the electromagnet with the result the armature bar is drawn upwardly and as soon as the lug 26 is passed thereover, completes its upper movement and lies in the path of return movement of this lug 26 thus latching the plunger in operative position so that the seat of the semaphore arm, which at this time is unbalanced due to the fact that the pivotal connection thereof is disposed at one side of its center, cannot 100 act through the flexible element 23 to withdraw the plunger 22. Attention is directed to the fact that the tendency of the semaphore 18 to return to its inoperative position, places a continual strain upon the plunger 22 insuring the proper engagement between contact lugs 26 and 30 and thereby 105 insuring proper completion of the circuit to the electromagnet until the train has left the electrified section of the railway. As soon as this occurs it will be obvious that the circuit to the electromagnet will be broken between the rails and the armature bar released 110 so that it may move downwardly. In order that the armature bar may not be frictionally held in elevated position by the engagement of the lugs 26 and 30, the faces 115 of these lugs which coat at this time are preferably beveled as indicated. The armature bar 30^a dropping downwardly and released, brings into engagement contacts 28 and 29 leaving the circuit in readiness for the next completion thereof by an occupation 120 of the electrified zone.

It will be obvious that a structure of this character is capable of a considerable range of use and that it may be very readily installed and attended. The breaking of the 5 relatively heavy solenoid current and maintenance of the relatively light current necessary to the electromagnetic latch, prevents too severe a strain upon the source of current and enables efficient operation of the 10 signal. From the source of current lead wires may be led to the semaphore for the purpose of illuminating the same during dark and twilight hours, one of these wires preferably having a switch S arranged 15 therein so that the circuit may be broken at other times. It will be furthermore obvious that the structural details of this device is shown as capable of a certain range of 20 change and modification and I have, therefore, not specified such details and do not wish to be understood as limiting myself to the general construction herein illustrated except as hereinafter claimed.

I claim:—

25 1. In a signal of the type described, a casing adapted to be buried in the highway and having a cover forming a portion of the highway, the cover having a slot, a semaphore arranged within the casing, a pivotal 30 mounting for the semaphore for shifting the same in its own plane to project through the slot in the casing and appear above the right of way, means for shifting the semaphore about the pivot thereof and a connection 35 between the semaphore and the mounting thereof permitting movement of the semaphore from a position vertical to the right of way to a position parallel with the right of way when impinged in a direction 40 longitudinal to the right of way.

2. In a signal of the type described, a casing adapted to be buried in the highway and having a cover forming a portion of the highway, the cover having a slot, a semaphore arranged within the casing, a pivotal 45 mounting for the semaphore for shifting the same in its own plane to project through the slot in the casing and appear above the right of way, means for shifting the semaphore about the pivot thereof and a connection 50 between the semaphore and the mounting thereof permitting movement of the semaphore from a position vertical to the right of way to a position parallel with the right of way when impinged in a direction 55 longitudinal to the right of way, the pivotal mounting of the semaphore being at one side of the center of the gravity thereof whereby said semaphore tends to automatically 60 return to concealed or inoperative position and means for locking the semaphore in elevated position.

3. In a signal for a grade crossing, rails and highways, a casing adapted to be disposed within the highway and having its

upper surface flush with the surface of the highway, said upper surface having a slot, a member pivoted within the casing for projection through the slot, electrical means for projecting the member through the slot rendered operative by occupation of a predetermined portion of the railway by a car, the pivotal mounting of the member being at one side of the center of gravity thereof whereby the member tends to automatically 70 return to concealed or inoperative position, means for latching the member against such a return movement and rendering said electrical operated means inoperative, said latching means being inoperative when such predetermined section of the railway is unoccupied by a car. 75

4. In a signal for a grade crossing, rails and highways, a casing adapted to be disposed within the highway and having its upper surface flush with the surface of the highway, said upper surface having a slot, a member pivoted within the casing for projection through the slot, electrical means for projecting the member through the slot rendered operative by occupation of a predetermined portion of the railway by a car, the pivotal mounting of the member being at one side of the center of gravity thereof whereby the member tends to automatically 90 return to concealed or inoperative position, means for latching the member against such a return movement and rendering said electrical operated means inoperative, said latching means being inoperative when such predetermined section of the railway is unoccupied by a car, and means for limiting the movement of the signal to operative and 95 inoperative position. 100

5. In a signal for a grade crossing, rails and highways, a casing adapted to be disposed within the highway and having its upper surface flush with the surface of the highway, said upper surface having a slot, a member pivoted within the casing for projection through the slot, electrical means for projecting the member through the slot rendered operative by occupation of a predetermined portion of the railway by a car, the pivotal mounting of the member being at one side of the center of gravity thereof whereby the member tends to automatically 110 return to concealed or inoperative position, means for latching the member against such a return movement and rendering said electrical operated means inoperative, said latching means being inoperative when such predetermined section of the railway is unoccupied by a car, the mounting of said member being such as to permit movement of the member from a position vertical to the right of way to a position parallel to the right of way when the member is in operative position and is impinged in a direction 115 longitudinal of the right of way. 120

125 130

6. In a signal including a semaphore movable to operative and inoperative positions and automatically returning from operative to inoperative position, operating means for said semaphore to shift the same to operative position and means for locking the operating means to prevent return of the sema-

phore to inoperative position including an electrically operated latch having latching parts forming contacts completing the circuit of the operating mechanism thereof. 10

In testimony whereof I hereunto affix my signature.

JOHN ENOCH YOUNGQUIST.
